UNITED STATES PATENT OFFICE

2,532,165

CONTAINER FOR REFUSE

Louis Hermani, Baltimore, Md., assignor to Continental Can Company, Inc., New York, N. Y., a corporation of New York

Application July 2, 1945, Serial No. 602,798

1 Claim. (Cl. 220—36)

1

The invention relates to new and useful improvements in a treadle operated covered refuse container.

An object of the invention is to provide a durable and serviceable container for refuse which is neat and compact and which contains few parts made, to a large extent, from sheet metal and can, therefore, be cheaply manufactured.

A further object of the invention is to provide a refuse container of the above type wherein the cover is raised by a rod disposed within the outer container and operated by an arm carried by a treadle operated shaft journaled in the body wall adjacent the lower end thereof.

A still further object of the invention is to provide a refuse container of the above type wherein the body of the outer container is beaded at its upper end to form a cover seat and wherein the cover is provided with a gasket adapted to engage said seat and seal the container.

These and other objects will in part be obvious and will in part be hereinafter more fully disclosed.

In the drawings which show by way of illustration one embodiment of the invention:

Figure 1 is a view partly in side elevation and partly in vertical section through the hinge joining the cover to the body of the outer container;

Figure 2 is a view in plan with a portion of the cover, the hinge for the cover, and the inner container removed to show the parts therebeneath.

Figure 3 is an enlarged vertical sectional view of a portion of the container at the hinge showing the cover raised;

Figure 4 is a side elevation of a portion of the container at the hinge as viewed from the rear.

The improved container for refuse includes an inner container for the refuse and an outer container which serves as a housing therefor. The outer container is made from sheet metal formed into a cylindrical body with the edges thereof joined in a side seam. The body portion is beaded at the upper end to form a cover seat and beaded at the lower end to form a support therefor. The cover overlies the bead on the upper end of the container body and is provided with a gasket which engages said bead. The hinge joining the cover to the body is made of sheet metal shaped so as to provide interengaging ears which are joined by a hinge pintle. The cover is raised by means of a rod located within the body portion of the outer container and which contacts an arm carried by the cover. This arm is made of sheet metal. The rod is guided by sheet metal brackets in its up and down move-

2

ments. The rod is raised by means of a shaft journaled in the body wall and carrying an arm which is connected to the rod. This shaft at the outer end thereof carries a treadle arm which is located outside of the container.

Referring more in detail to the drawings, the refuse container includes a body portion 1 made of sheet metal with the edge portions thereof joined by a side seam 2. The upper end of the body portion is rolled outwardly into a hollow bead 3 which serves as a seat for the cover. The lower end of the body portion is rolled outwardly into a hollow bead 4 which serves as a support for the container. This hollow bead 4 is at the lower end of the body and therefore the body, when it rests on the support, is closed at its lower end by the support.

The body portion is closed at its upper end by a cover 5. The cover has a projecting flange 6 which overhangs the seat formed by the bead 3 of the body portion. The peripheral portion of the cover is shaped upwardly so as to provide a recess for a gasket 7. The outer edge of the cover is curved inwardly so as to support the gasket. This gasket is so disposed as to engage the seat formed by the bead 3. The gasket extends all the way around the container and this will seal the outer container when the cover is closed.

A hinge bracket 8 made of sheet metal is secured to the body portion below the bead 3 by rivets 9, 9. This hinge bracket has parallel side walls 10, 10 and a rear wall which is curved at 11 about an opening 12 in the side walls. These openings 12 are adapted to receive a hinge pintle 13. The side walls form supporting ears for this hinge pintle. A hinge bracket is secured to the cover. This bracket is made of sheet metal and includes an upper wall 14 with depending side walls 15 carrying ears 16 which engage the pintle 13. This cover hinge bracket is secured to the cover by rivets 17.

The upper wall 14 of the cover bracket is shaped to conform to the curved wall 11 of the body bracket and when the cover is raised to an open position this wall 14 will prevent the cover from swinging back too far. It is always desirable that the cover should be moved to an open position where when released, it will close by gravity as shown in Figure 3.

The cover is raised by a treadle mechanism which operates upon a rod 18. This rod slides in a sheet metal bracket 19 near the lower end of the rod and a sheet metal bracket 20 near the upper end of the rod. These brackets are at-

tached to the inner surface of the body wall and the rod is located wholly within the body of the outer container. The rod at its upper end is bent laterally as indicated at 21 and is adapted to engage a sheet metal bracket 22 riveted to the cover and bent so as to provide an arm which contacts the upper end of the rod when the rod is raised so that the cover will be lifted to its open position as shown in Figure 3. The lower end of the rod is bent inwardly, thence upwardly and thence backwardly upon itself, as indicated at 23. When the rod is raised this inwardly bent portion will engage the bracket 19 as a stop, limiting the upward movement of the rod, and thus limit the upward movement of the cover. The parts are so dimensioned that the rod will remain in contact with the bracket arm on the cover when the cover is in fully raised position with the rod engaging the stop at the lower end thereof.

The rod is raised and lowered by a shaft 24 journaled in the body portion of the outer container a short distance above the supporting bead therefor. This shaft extends radially inward from the body wall for a short distance and thence laterally to form an arm 25 extending to a point near the lower end of the rod 18 and thence in a direction substantially parallel to the shaft 24, as indicated at 26. This portion of the shaft 26 extends through the loop formed by the bent-back portion 23 of the rod 18. This loop of the bent-back portion is of sufficient length so that the shaft may be oscillated about its pivotal connection with the body wall for the raising and lowering of the rod 18. This shaft 24 on the outside of the container is bent at right angles as indicated at 27 and a metal foot-pad 28 is attached to its other end. The foot-pad is shaped to conform to the container wall and forms a relatively broad support for the foot of the operator.

The refuse is placed in an inner container 29 which is made of sheet metal. The upper end of this container is beaded as indicated at 30. The lower end of the container is seamed to a bottom 31 in the usual way. A bail 32 is pivoted to ears 33 secured to the inner face of the body wall of the inner container 29. This inner container 29 is so dimensioned that it may be readily placed in the outer container and will be supported by the inwardly extending portion of the shaft 24 which raises and lowers the cover.

The cover is provided with a relatively small cup 34 consisting of two parts having a threaded engagement and one of the parts is riveted to the center of the cover so that it can be shifted circumferentially on the rivet. The other part is perforated at 36 and in this cup may be placed an antiseptic. The cover is provided with a vent hole 35. The portion of the cup which is secured to the cover may be rotated so as to bring

an opening 37 therein into register with the opening 35 to a lesser or greater extent for venting the container.

It is obvious that minor changes in the details of construction may be made without departing from the spirit of the invention as set forth in the appended claim.

I claim:

10 A refuse container comprising an outer receptacle including a sheet metal body rolled outwardly at its upper end to form a continuous bead and rolled outwardly at its lower end to form a bead for supporting the body, a cover for said body, said cover being extended beyond said bead at the upper end of the body and having a gasket holding recess centered over said bead, a continuous unbroken gasket secured to the cover in said recess, said gasket being substantially flush with the inner face of said cover and adapted to engage the bead at the upper end of the body, a hinge bracket secured to the outer face of the body and projecting rearwardly therefrom, a hinge bracket connected to the outer face of the cover and projecting rearwardly therefrom, said hinge brackets having engaging ears and a pintle passing through said ears for pivotally supporting the cover on said body, said pintle being disposed in a plane defined by the upper portion of the body whereby the weight of the cover when closed will cause the gasket to sealingly contact with said bead at the upper end of the body throughout the entire extent of the bead, said body having spaced guiding brackets on the inner face thereof, a rod mounted for reciprocation in said brackets, a bracket mounted on the under face of said cover and disposed radially within the gasket adapted to be engaged by said rod for raising the cover, a shaft journaled in the body wall of the container adjacent the bottom end thereof and carrying an arm connected to the rod for lifting the same, a treadle located outside of the body and connected to the shaft for oscillating the shaft, and an inner receptacle disposed within the body of said outer receptacle.

LOUIS HERMANI.
